UNITED STATES PATENT OFFICE.

ERNEST W. EVANS, OF ROBINSON, ILLINOIS.

APPLIANCE FOR HOT-WATER HEATING SYSTEMS.

1,247,097.

Specification of Letters Patent.

Patented Nov. 20, 1917.

Application filed May 23, 1916, Serial No. 99,379.

Renewed October 8, 1917. Serial No. 195,453.

To all whom it may concern:

Be it known that I, ERNEST W. EVANS, a citizen of the United States, residing at Robinson, in the county of Crawford and 5 State of Illinois, have invented certain new and useful Improvements in Appliances for Hot-Water Heating Systems, of which the following is a specification.

This invention has as its object to provide 10 an appliance for installation in hot water heating systems of the gravity type for the purpose of rendering such systems more effective generally.

The appliance embodying the present invention is designed to quicken the circulation 15 in the system and to increase the heating capacity of the system. The presence of the appliance in a hot water heating system results in an increase in pressure in the 20 system which produces increased circulation and therefore renders the system equally as efficient as a steam heating system so far as range of temperature is concerned.

The invention also aims to provide an appliance for the purpose stated above which 25 will remedy existing defects in a system of the class mentioned above, such for example as insufficient radiation, sluggish circulation, boiling of the water from quick firing, etc.

Another aim of the invention is to so construct the appliance that the same will be 30 entirely automatic and in view of the beneficial results secured by its use, will eventually lessen the cost of installation of the 35 hot water heating system of which it constitutes a part.

In the accompanying drawings:

Figure 1 is a view in elevation of the device embodying the present invention and 40 the hot water heating system in which it is installed.

Fig. 2 is a perspective view of the appliance.

Fig. 3 is a vertical longitudinal sectional 45 view therethrough.

Fig. 4 is a horizontal sectional view on the line 4—4 of Fig. 3.

In Fig. 1 of the drawings there is illustrated 50 an ordinary hot water heating system of which the boiler is indicated by the reference character A, one of the radiators by the reference character B, the expansion pipe by the reference character C, and the expansion tank by the reference character 55 D, this tank being, as is usual, located a suit-

able distance above the level of the highest radiator of the system.

The appliance embodying the present invention comprises a casing indicated in general by the reference numeral 1 and comprises a top 2, sides 3, and end walls 4 and 5, the casing being provided at its end at which the wall 4 is located, with a water leg 9. The casing is also provided with a bottom 7 and in its end wall 5 above its 60 said bottom with an opening 8 to receive a section of the expansion pipe C of the system. In a like manner the end wall 4 of the casing is provided with an opening 9 receiving the end of the other section of the 65 pipe C, the first mentioned section leading from the boiler and the last mentioned section leading from the casing 1 to the expansion tank D, as clearly shown in Fig. 1 of the drawings. The casing is provided 70 interiorly with partitions 10 which extend between the side walls 3 thereof and upwardly from the bottom 7 at an angle inclined toward the end wall 5 of the casing. The upper ends of the partitions 10 terminate a 75 short distance below the plane of the top 2 of the casing and the said top of the casing is provided with partitions 11 which extend downwardly therefrom and between the side walls 3 of the casing and each terminate at 80 their lower edges a short distance above the plane of the bottom 7 of the casing; each of the partitions 11 extending between two adjacent ones of the partitions 10 as shown in 85 Figs. 3 and 4 and the said partitions 11 being inclined downwardly in the direction of the said end wall 5 of the casing. The top 90 2 of the casing is also provided with depending partitions 12 which are relatively short and extend between the sides 3 and these 95 partitions are inclined downwardly in the direction of the end wall 4 of the casing and each faces the upper portion of that face of the respective partition 10 which is presented toward the end wall 4 of the casing. 100 The numeral 13 indicates a baffle partition which is integral with the inner surface of the wall 5 of the casing and this partition 13 is inclined downwardly toward the bottom 7 of the casing and is located directly opposite the opening 8. In a like manner the end wall 4 of the casing is formed with 105 110

a baffle partition 14 which is inclined downwardly toward the bottom of the casing and which is located opposite the upper side of the opening 9 and extends part way across 5 the water leg 6.

For a purpose to be presently explained, a bypass pipe 15 is mounted upon one side of the casing near the bottom thereof and opens at its ends into the said casing, one 10 end of the pipe communicating with the casing between the end wall 5 and the next adjacent partition 10 and below the baffle partition 13, and the other end of the pipe communicating with the casing between the 15 end wall 4 and the next adjacent partition 10 and substantially opposite the lower edge of the baffle partition 14. Interposed in the pipe 15 is a check valve indicated in general by the numeral 16.

From the foregoing description of the invention it will be understood that when the system is initially filled with water, water entering the casing 1 will first fill the space between the end wall 5 and the partition 10 20 next adjacent thereto and will then flow over the upper edge of this partition into the space between the said partition and the next adjacent partition 10 and as the water level rises between these partitions and 25 reaches the lower edge of that one of the partitions 11 which extends therebetween, the air in the space between the end wall 5 and the said partition 11 will be trapped and in a like manner air will be trapped between 30 the first mentioned partition 11 and the other one of the partitions 11 and also between the last mentioned partition 11 and the end wall 4 of the casing. The presence of the appliance in the system results in 35 the water being subjected to a pressure of from seven to ten pounds per square inch and it will be understood that upon increase in pressure above the degree stated, a certain volume of the water within the 40 casing 1 will be caused to pass beneath the lower edges of the partitions 11 and over the upper edges of the partition 10 and into the expansion tank D by way of the pipe C. When the system is put out of operation or 45 requires an additional volume of water the water will flow from the tank D down through the pipe C and through the pipe 15 and past the valve 16 from the right hand to the left hand end of the casing 1. It will 50 be understood, however, that water cannot pass through the pipe 15 in the opposite direction. It will be understood, of course, that the partitions 12 serve to prevent the 55 trapped air being blown out from the casing of the appliance.

It will also be understood that in freezing weather there will be no danger of the pipes of the system in which the invention is installed, bursting due to freezing of the 60 water in the expansion tank inasmuch as

even if the water does freeze in this tank the trapped air in the casing of the appliance will serve as a cushion to equalize the expansive force of the water.

Where relatively great radiation is required the pressure in the system may be increased by increasing the number of partitions 10, 11 and 12. 70

It will be understood that the appliance may be located on the same floor with and 75 under the expansion tank equally as well as in the position illustrated in the drawings.

By inclining the partitions 10 and 11 in the manner shown in the drawings and hereinbefore described, the spaces within which 80 the water rises are decreased in size toward the upper portion of the appliance and therefore a relatively high pressure is obtained with a less volume of water than if the partitions were located in parallel planes. 85

Having thus described the invention, what is claimed as new is:

1. In an appliance of the class described, a casing having a water inlet at one side and a water outlet at the opposite side, partitions extending upwardly from the bottom of the said casing, partitions extending downwardly from the top of the said casing between the first mentioned partitions, and relatively short partitions extending downwardly from the top of the casing and each located laterally opposite the upper end of one of the first mentioned partitions. 90

2. In an appliance of the class described, a casing having a water inlet at one side and a water outlet at the opposite side, partitions extending upwardly from the bottom of the said casing, partitions extending downwardly from the top of the said casing, between the first mentioned partitions, and 100 baffle partitions located substantially opposite the inlet and outlet of the casing. 105

3. In an appliance of the class described, a casing having a water inlet at one side and a water outlet at the opposite side, partitions extending upwardly from the bottom of the said casing and inclined upwardly toward one end wall thereof and terminating short of the top of the casing, and partitions extending downwardly from the top of the casing and inclined downwardly toward the said end wall of the casing and terminating short of the bottom of the casing. 110

4. In an appliance of the class described, a casing having a water inlet at one side and a water outlet at the opposite side, partitions extending upwardly from the bottom of the said casing, partitions extending downwardly from the top of the said casing, 115 the partitions terminating respectively short of the top and bottom of the casing, and relatively short baffle partitions extending downwardly from the top of the casing and located each relatively close to the upper 120

end of one of the first-mentioned partitions and opposite the same, the lower ends of the said baffle partitions terminating below the upper ends of the said first-mentioned partitions.

5. In an appliance of the class described, a casing having a water inlet at one side and a water outlet at the opposite side, partitions extending upwardly from the bottom 10 of the said casing, one of said partitions being located near the inlet side of the casing and another one of the partitions being located near the outlet side of the casing, partitions extending downwardly from the top 15 of the casing between the first-mentioned

partitions, a baffle partition extending inwardly and downwardly from the inlet side of the casing substantially opposite the said inlet and terminating relatively close to the lower portion of the adjacent one of the 20 first-mentioned partitions, and a baffle partition extending inwardly and downwardly from the outlet side of the casing and located substantially opposite the said outlet and terminating relatively close to the lower 25 portion of the adjacent one of the first-mentioned partitions.

In testimony whereof I affix my signature.

ERNEST W. EVANS.
